UNITED STATES PATENT OFFICE.

SAMUEL A. ANDREWS, OF TACOMA, WASHINGTON.

DESIGN FOR A BADGE.

SPECIFICATION forming part of Design No. 32,893, dated July 3, 1900.

Application filed May 22, 1900. Serial No. 17,610. Term of patent 7 years.

To all whom it may concern:

Be it known that I, SAMUEL A. ANDREWS, a citizen of the United States, residing at Tacoma, in the county of Pierce and State of Washington, have invented and produced a new and original Design for a Badge, of which the following is a specification.

This invention relates to a design for a badge, and the essential feature resides in a shield with a facing eagle thereon with wings spread and the tip portions of the latter extended beyond the side edges of the shield.

The drawing illustrates an elevation of the design, and referring thereto the numeral 1 designates a shield having an upper field 2 of a blue color and a lower body having alternate stripes of red and white enamel or other material. Across a portion of the body a seg-

mental scroll 3 extends, and on the latter rests an eagle 4. The wings of the eagle are spread and the tips 5 are projected beyond the upper side portions of the shield. The eagle also faces to the front and the body is erect, with a portion of the tail shown below the scroll.

Having thus described the invention, what is claimed as new is—

The design for a badge, herein shown and described.

In testimony that I claim the foregoing as my own I have hereto affixed my signature in the presence of two witnesses.

SAMUEL A. ANDREWS.

Witnesses:

HERMAN KLABER,
JACOB ANDREWS.
